W. G. BUNNELL

ROAD GRADER

Filed April 8, 1925

Patented Mar. 16, 1926.

1,576,808

UNITED STATES PATENT OFFICE.

WILLARD G. BUNNELL, OF GILLETTE, WYOMING.

ROAD GRADER.

Application filed April 8, 1925. Serial No. 21,650.

To all whom it may concern:

Be it known that I, WILLARD G. BUNNELL, a citizen of the United States, residing at Gillette, in the county of Campbell and State 5 of Wyoming, have invented certain new and useful Improvements in Road Graders, of which the following is a specification.

This invention seeks to provide a simple, strong and durable machine of novel construction which may be easily operated and 10 efficiently employed for grading roads, leveling land surfaces, making ditches, clearing land of brush or removing snow from highways or feeding yards, and 15 various other similar operations. The invention is illustrated in the accompanying drawing and will be hereinafter fully described, the novel features being particularly pointed out in the appended claims.

20 In the drawings:

Figure 1 is a plan view, partly broken away and in section, of a machine embodying my present invention;

25 Fig. 2 is a side elevation of the same, and

Fig. 3 is a transverse section on the line 3—3 of Fig. 1.

In carrying out my invention, I employ 30 two side bars 1 which may be of any desired dimensions and are duplicates in construction, the said bars being each beveled at one end, as indicated at 2, whereby they may be fitted together in divergent relation, as clearly shown in Fig. 1. At proper 35 intervals in the lengths of these side bars, cross bars or beams 3 and 4 are secured to and extend between the same so that the side bars will be very firmly braced and the machine given the strength necessary 40 to resist the strains placed thereon when at work. Upon the forward cross bar 3 is pivotally mounted a drawbar 5 which is held to the said cross bar by a bail 6 secured at its ends upon the cross bar and 45 having its intermediate portion bridging the drawbar and perforated to receive a pivot pin 7 whereby the drawbar is held in place. The drawbar is provided at its front end with a transverse opening 8 to 50 facilitate the attachment of a draft device thereto and its rear end extends over and rests upon the rear cross bar 4, as shown. A guard 9 is secured at its ends upon the 55 upper edges of the side bars 1 or the ends of the cross bar or brace 4 and its inter-

mediate portion passes over the drawbar so as to hold the same against upward displacement, and a retaining pin 10 is engaged through any one of a series of openings 11 in the guard 9 and corresponding 60 openings 12 in the drawbar to engage one of the sockets 13 in the upper edge of the brace so that the drawbar will be held in any position in which it may be set.

To the outer face of each side bar, I 65 secure a blade 14 consisting of a substantial steel plate running the entire length of the side bar and having its lower edge curved outwardly and sharpened, as indicated at 15. The forward end of each 70 blade extends forwardly beyond the side bars, and these projecting extremities of the blades are brought into juxtaposition, as shown at 16, and firmly secured together, the forward edges thereof being sharpened 75 and inclined slightly upwardly and rearwardly, as will be understood upon reference to Fig. 2.

The manner of using the machine will, it 80 is thought, be readily understood from the foregoing description, taken in connection with the accompanying drawing. Draft is applied to the front end of the drawbar 85 so that the machine will be drawn over the road or ground surface and, as it moves forwardly, the front projecting extremities of the blades will penetrate the soil or other material and will cut through the same, being followed immediately by the lower outturned sharp edges 15 of the 90 blades so that a ditch will be formed and the dirt turned aside. If it be desired to spread the removed soil equally at the opposite sides of the machine, the drawbar is arranged along the central longitudinal 95 line of the machine, as shown by dotted lines in Fig. 1, but, if it be desired to turn the dirt to one side, the rear end of the drawbar is shifted to the opposite side of the machine, as shown by full lines in 100 Fig. 1, whereupon, if draft be applied to the front end of the drawbar, the nearer side of the machine will merely serve as a landside to hold the machine to its work while the opposite side will cut away the 105 dirt to form a ditch and will throw the dirt outwardly to the side of the ditch.

The machine is exceedingly simple in construction and may be built at a very 110 low cost. Obviously, it may be used for a

2

great number of different purposes and, when employed as a snow plow, will effectually throw the snow to both sides of the path being formed so that the cleaning of 5 the path will be rapidly accomplished. The machine may be used for removing brush and similar growth from a field, and will operate efficiently for this purpose inasmuch as the sharpened edges of the blade 10 will cut through the stalks of the brush immediately at the surface of the ground so that the field will be very rapidly cleared. The machine may be used upon a hillside as well as upon a comparatively level surface 15 so that terraces may be formed as easily as ditches are produced.

Having thus described the invention, I claim:

1. A machine for the purpose set forth comprising divergent side bars having abutting front ends, braces extending between the side bars, means connected with the braces for applying propelling force to the side bars, and blades secured to the outer 20 faces of the side bars and extending the full length thereof, the lower edges of the blades being turned outwardly and sharpened and the front extremities of the blades being secured together in abutting relation in advance of the side bars on a line bisecting 30 the angle defined by the side bars.
2. A machine for the purpose set forth comprising divergent side bars, blades secured to the outer faces of the side bars, braces secured to and extending between the 35 side bars, a bail secured upon the forward brace, the rearmost brace having a plurality of sockets in its upper edge, a drawbar extending through said bail and having its rear end resting upon the rear brace, a 40 guard extending from end to end of the rear brace over the drawbar, a pin engaged through the bail and the drawbar to pivotally retain the drawbar upon the forward brace, and a pin engageable through the 45 guard and the drawbar to enter one of the sockets in the rear brace to hold the drawbar in a set relation to the rear brace.

In testimony whereof I affix my signature.

WILLARD G. BUNNELL. [L. S.]
